UNITED STATES PATENT OFFICE.

ALEXANDER FERDINAND VICTOR, OF DAVENPORT, IOWA.

MECHANICAL MOVEMENT.

1,198,683.

Specification of Letters Patent. Patented Sept. 19, 1916.

Application filed March 23, 1916. Serial No. 86,048.

To all whom it may concern:

Be it known that I, ALEXANDER FERDINAND VICTOR, a subject of the King of Sweden, (having declared my intention of becoming a citizen of the United States,) residing at Davenport, in the county of Scott and State of Iowa, have invented new and useful Improvements in Mechanical Movements, of which the following is a full, 10 clear, and exact description.

My invention relates to improvements in mechanical movements, and particularly to the movement known as a Geneva movement for producing an intermittent movement for 15 advancing the film through a moving picture machine.

The object of my invention is to provide an intermittent movement in which the driving member imparts a movement to the 20 driven member that has a slow beginning and a slow ending and is very fast between the same and that also exerts a greater leverage on the driven member when the stud that transmits the movement passes the imaginary line drawn through the axes of both 25 members. This I accomplish by the means hereinafter fully described, and as particularly pointed out in the claims.

In the drawings: Figure 1 is a longitudinal central section through my invention. Fig. 2 is a transverse section taken on dotted line 2—2, Fig. 1. Figs. 3, 4 and 5 are corresponding transverse sections taken on dotted line 3—3, Fig. 1, and showing the driving 35 and driven members of my invention in different operative positions relative to each other.

Referring to the drawings, A represents a suitable support for the spindle *a*. This 40 spindle is cylindrical and one end thereof is securely fastened in said support by means of pins *b*, *b*, and it projects laterally therefrom a suitable distance. A sleeve *B* is loosely mounted on this spindle *a* and the 45 end thereof next its support terminates in an integral gear *C*, and about midway its ends it has a disk *c* mounted thereon that is made integral therewith. This disk, on the side thereof facing gear *C*, has a circular flange 50 *D* projecting therefrom the diameter of which is such that it comes midway between the circumference of the sleeve and the disk. A segment of this flange is cut away, and a 55 stud *E* projects from the same side of disk *c* as flange *D* at a point outside of the circumference of said flange and in such a position

that its center is intersected by an imaginary line extending radially from the center of spindle *a* midway between the ends of the cut away portion of flange *D*.

A suitable distance above spindle *a* and parallel thereto, I journal a shaft *F* in bearings *d*, which latter is journaled in a suitable stationary frame-work *e*. The bore of bearings *d* in which shaft *F* is journaled is eccentric, and the end of said bearings *d* terminating above gear *C* is provided with a circumferential flange *g* which can be grasped so as to turn the bearings and adjust the distance of shaft *F* from spindle *a* so as to take up the wear of the gearing connecting the sleeve and said shaft. Shaft *F* has a circular head *G* on the end thereof extending beyond the flanged end of bearings *d*, and the width of said head opposite said bearings is provided with three equi-distant radially disposed channels *H*, *H'*, *H*², which communicate at the center of the head. The axis of head *G* is such a distance from the axis of spindle *a* that when disk *c* revolves 80 stud *E* will, when said head is in proper position, enter channel *H* thereof, as shown in Fig. 3. In order to insure said head *G* being in its proper position for stud *E* to thus engage one of its channels, the periphery of 85 the channeled part of the same between the mouths of said channels is concaved to provide seats *K*, substantially as shown in Figs. 3, 4 and 5, and seat *K* nearest spindle *a* will be engaged by the outer circumference of flange *D* and said head thereby prevented 90 from revolving, except when stud *E* engages the channels in the face of said head.

When stud *E* first engages one of said channels the advanced end of the segmental opening in flange *D* will have reached such a rotative position that said stud will start the head rotating very slowly, and when said advanced end of said segmental opening reaches and passes the imaginary line intersecting the axes of spindle *a* and head *G* the rotated movement of the head will be very fast and continue to be fast until the rear end of said segmental opening comes in contact with and engages the adjacent concaved side of the head, whereupon the motion of the head will slow up as the stud passes out of the same channel to the right of the vertical plane of the axis of said head, as shown in Fig. 5 of the drawings.

If stud *E* were cylindrical the sides thereof intersected by a transverse line drawn at

right angles to the radial line connecting its center to the center of spindle *a* comes in contact with the sides of the channels, and assuming the relative position of the said 5 stud to be that shown in Fig. 4 of the drawings, the leverage it would exert upon the head when imparting its movement thereto would be much less than if said stud came in contact with the sides of said channels at 10 a distance farther from the center of the head. This I accomplish by making said stud of a somewhat right angle triangular shape in cross-section, or with three sides that are practically straight or slightly convexed, substantially as shown. By means of 15 this construction the said stud is enabled to engage the sides of the channel at a comparatively greater distance from the center of head *G* and thus exert greater leverage. 20 This is a very important feature of my invention, as experience has demonstrated that its point of contact with the sides of the channels avoids such a near approach to the center of the head as to lock the same as 25 some times happens when a cylindrical stud is used.

Disk *c* and head *G*, together with the features thereof that enable said disk to impart an intermittent movement to head *G* and 30 shaft *F* are inclosed in a suitable metal casing *J*, which consists of two parts of substantially the same shape, that are suitably secured together by screws or rivets *I* and are supported by being mounted upon the 35 extended end of shaft *F* between head *G* and bearings *g* and upon sleeve *B* between gear *C* and flange *D*.

The end of sleeve *B* extending beyond disk *c* has a balance-wheel *L* secured thereon, and 40 this balance-wheel is of greater circumference than casing *J*, and has its edge *M* flanged toward and surrounds a portion of casing *J*, substantially as shown. The balance-wheel while not absolutely essential is 45 desirable in order to obtain an even rotary movement of disk *c*.

What I claim as new is:—

1. A mechanical movement of the kind specified comprising a rotatable spindle having 50 a concentric circular member mounted thereon projecting from one side thereof, a part of the periphery of which is cut away, and a stud which is triangular in cross-section and projects therefrom outside of the circumference of said circular member midway between the radial lines intersecting the ends of the cut away part, and a revolute head having a plurality of radial channels adapted to be engaged by said stud and 55 having the periphery thereof between the equi-distant mouths of said channels curved to fit the circumference of said circular member.

2. A mechanical movement of the kind 60 specified comprising a rotatable spindle hav-

ing a concentric circular disk mounted thereon that has a concentric circular member projecting from one side thereof, a part of the periphery of which is cut away, a stud projecting therefrom outside of the 70 circumference of said circular member midway between radial lines intersecting the ends of said cut away part, a sleeve on which said disk is mounted, a revolute head having a plurality of radial channels 75 adapted to be engaged by said stud, and having the periphery thereof between the equi-distant mouths of the channels concaved, a shaft on which said head is mounted, a bearing in which said shaft is 80 journaled, the bore of which is eccentric to its axis, and a suitable support in which said bearing is rotatably adjustable.

3. A mechanical movement of the kind 85 specified comprising a rotatable spindle having a concentric circular disk mounted thereon that has a concentric circular member projecting from one side thereof, a part of the periphery of which is cut away, a stud which is triangular in cross section and 90 projects therefrom outside of the circumference of said circular member midway between radial lines intersecting the ends of said cut away part, a sleeve on which said disk is mounted, a revolute head having a 95 plurality of radial channels adapted to be engaged by said stud and having the periphery thereof between the equi-distant mouths of the channels concaved, a shaft on which said head is mounted, a bearing in which 100 said shaft is journaled, the bore of which is eccentric to its axis, and a suitable support in which said bearing is rotatably adjustable.

4. A mechanical movement of the kind 105 specified comprising a rotatable spindle having a concentric circular disk mounted thereon that has a concentric circular member projecting from one side thereof, a part of the periphery of which is cut away, a stud projecting therefrom outside of the circumference of said circular member midway between radial lines intersecting the ends of 110 said cut away part, a sleeve on which said disk is mounted, a revolute head having a plurality of radial channels 115 adapted to be engaged by said stud and having the periphery thereof between the equi-distant mouths of the channels concaved, a sleeve on which said disk is fixedly mounted, a stationary spindle upon which said sleeve is 120 loosely mounted, a balance-wheel secured on the outer end of said sleeve, a shaft on which said head is mounted, a bearing in which said shaft is journaled the bore of which is eccentric to its axis, and a suitable support 125 in which said bearing is rotatably adjustable.

5. A mechanical movement of the kind 130 specified comprising a rotatable spindle having a concentric circular disk mounted

thereon that has a concentric circular member projecting from one side thereof, a part of the periphery of which is cut away, a stud projecting therefrom outside of the circumference of said circular member midway between radial lines intersecting the ends of said cut away part, a sleeve on which said disk is mounted, a revoluble head having a plurality of radial channels 10 adapted to be engaged by said stud, and having the periphery thereof between the equi-distant mouths of the channels concaved, a shaft on which said head is mounted, a bearing in which said shaft is journaled the bore of which is eccentric to its axis, a 15 suitable support in which said bearing is rotatably adjustable, and a casing inclosing said disk and said head and supported on said shaft and the sleeve of said disk.

In witness whereof I have hereunto set 20 my hand this 13th day of March, 1916.

ALEXANDER FERDINAND VICTOR.
